(57) CLAIM

I claim the ornamental design for a plush toy, as shown and described.

DESCRIPTION

FIG. 1 is a perspective view of a plush toy embodying the present invention.

FIG. 2 is front view of the plush toy of FIG. 1.

FIG. 3 is right side view of the plush toy of FIG. 1.

FIG. 4 is a left side view of the plush toy of FIG. 1.

FIG. 5 is a rear view of the plush toy of FIG. 1.

FIG. 6 is a top view of the plush toy of FIG. 1; and, FIG. 7 is a bottom view of the plush toy of FIG. 1.

The broken lines illustrate environment and form no part of the claimed design.
